SPECTACLE FRAME FRONT

Dale E. Megee, New York, N.Y., assignor to Liberty
Optical Manufacturing Co., Inc., Newark, N.J.

Filed Sept. 16, 1965, Ser. No. 87,032

Term of patent 14 years

(Cl. D57—1)

FIG. 2

FIG. 3

FIG. 4

FIG. 6

FIG. 5

FIG. 7

FIG. 8

FIG. 9

FIG. 10

FIG. 11

FIG. 12

FIG. 1 is a front view of a spectacle frame front embodying my new design.

FIG. 2 is a top view of the spectacle frame front shown in FIG. 1.

FIG. 3 is a bottom view of the spectacle frame front shown in FIG. 1.

FIG. 4 is a cross sectional view taken on line 4-4 of FIG. 1.

FIG. 5 is a cross sectional view taken on line 5-5 of FIG. 1.

FIG. 6 is a cross sectional view taken on line 6-6 of FIG. 1.

FIG. 7 is a cross sectional view taken on line 7-7 of FIG. 1.

FIG. 8 is a front view of a modified form of the spectacle frame front shown in FIG. 1.

FIG. 9 is a top view of the spectacle frame front shown in FIG. 8.

FIG. 10 is a bottom view of the spectacle frame front shown in FIG. 8.

FIG. 11 is a cross sectional view taken on line 11-11 of FIG. 8.

FIG. 12 is a cross sectional view taken on line 12-12 of FIG. 8.

The dominant features of my new designs reside in the portions shown in full lines.

I claim:

The ornamental design for a spectacle frame front, as shown and described.
